US00D338237S

United States Patent [19]

Buist et al.

[11] Patent Number: Des. 338,237

[45] Date of Patent: ** Aug. 10, 1993

[54] MOLECULAR MODEL

[76] Inventors: Peter H. Buist, 124 Fieldgate Drive, Nepean, Ontario, Canada, K2J 1T9; Alois A. Raffler, 20 Whitewood Ave, Manotick K0A 2N0, Canada

[**] Term: 14 Years

[21] Appl. No.: 447,505

[22] Filed: Dec. 7, 1989

[30] Foreign Application Priority Data

Jul. 10, 1989 [CA] Canada 10-07-89-8

[57] CLAIM

The ornamental design for a molecular model, as shown and described.

DESCRIPTION

FIG. 1 is a perspective view of the molecular model showing one embodiment of our new design;

FIG. 2 is a side elevational view of a first one-third portion of the embodiment of FIG. 1;

FIG. 3 is a side elevational view of a second one-third portion of the embodiment of FIG. 1;

FIG. 4 is a side elevational view of a third one-third portion of the embodiment of FIG. 1;

FIG. 5 is a top plan view of the embodiment of FIG. 1;

FIG. 6 is a bottom plan view of the embodiment of FIG. 1;

FIG. 7 is a perspective view of the molecular model showing a second embodiment of our new design;

FIG. 8 is a side elevational view of a first one-third portion of the embodiment of FIG. 7;

FIG. 9 is a side elevational view of a second one-third portion of the embodiment of FIG. 7;

FIG. 10 is a side elevational view of a third one-third portion of the embodiment of FIG. 7;

FIG. 11 is a top plan view of the embodiment of FIG. 7; and,

FIG. 12 is a bottom plan view of the embodiment of FIG. 7.

FIG. 1

FIG. 2

FIG.3

FIG.4

FIG. 6

FIG. 8

FIG. 9

FIG. 10

FIG. 11

FIG. 12
